UNITED STATES PATENT OFFICE.

JOHN O. VOGEL, OF ROCHESTER, NEW YORK.

METAL ROOFING.

SPECIFICATION forming part of Letters Patent No. 242,082, dated May 24, 1881.

Application filed March 26, 1881. (No model.)

To all whom it may concern:

Be it known that I, JOHN O. VOGEL, of Rochester, in the county of Monroe and State of New York, have invented certain Improvements in 5 Metal Roofing, of which the following is a specification.

The main object of this invention is to construct a sheet-metal roof in such manner as to avoid the opening or breaking of the joints or 10 seams by the contraction of the metal; and to this end it consists in forming the roof of plates of tin or other sheet metal, each having its entire surface corrugated, these sheets being seamed together or otherwise united at the 15 edge in any ordinary or suitable manner, whereby a roof is produced the seams of which are of greater length than the surface of the roof.

The invention also consists in the manner of preparing the corrugated sheets, consisting 20 in first corrugating them in one direction and subsequently in another direction, for the purpose of shortening the sheets both ways, so that in the process of making the seam the seam becomes wavy, and consequently of greater length 25 than the body of sheet.

Referring to the accompanying drawings, Figure 1 represents a perspective view of the prepared sheet; Fig. 2, an edge view of the same; Fig. 3, a perspective view of a portion 30 of a roof constructed of the improved plates.

In preparing the improved plates flat sheets of tin or other suitable material, such as are ordinarily used in the construction of sheet-metal roofs, are passed between corrugating-rolls or corrugating-machines, or device of any 35 suitable construction, and corrugated throughout their entire surface in one direction. After this first corrugation the plates are again passed through the machine and corrugated in another and different direction, the plates being 40 in this manner shortened in two directions. It is preferred that the corrugation should run diagonally or obliquely across the sheets at substantially right angles to each other; but 45 their course may be modified. After the sheets are corrugated the edges are formed for the purpose of uniting the sheets or making the seams. The operation of closing the seam has the effect of increasing the length of the edges 50 or seams and gives them a wavy or buckled

appearance, and counteracts the effect of expansion and contraction of the seams, the corrugation in the body of the sheet acting in the same capacity for the central portion of each sheet.

The sheets, being constructed as above described, are laid in position and seamed together or otherwise united at their edges in any ordinary or suitable manner, the result being the production of a roof in which the joints are 60 of greater length than the roof-surface, the joints or seams presenting a vertical, waved, or sinuous appearance.

It is found that the roof thus constructed is entirely free from the ordinary danger of rupture in the joints or seams when the metal is contracted by exposure to a low temperature.

In roofs of ordinary construction having flat seams or joints of the same length as the body of the plates, the contraction of the metal causes 70 the joints to open or the metal to be ruptured; but in the improved form of roof herein presented the contraction of the metal serves merely to take up the surplus length of the joints or seams and render them straight, or approximately so, without in the least straining the joints.

We are aware that roof-plates have been provided with central corrugations, and we make no claim, broadly, thereto, our invention being 80 restricted to plates wherein two parallel edges are of greater length than the central or body portion between them.

While it is preferred to make use of the corrugations, our invention is designed to embrace 85 any and all plates, whether corrugated or not, the edges of which are of greater length than the body of the plate.

Having thus described the invention, what is claimed is—

1. The metal sheet for roofing purposes having the central corrugated portion and the flattened edges of a length greater than lines drawn parallel therewith through the middle of the sheet.

2. The sheet-metal roofing-plate having its entire surface corrugated in two directions for the purpose of shortening the same in both directions, whereby the formation of the seams in applying the plates will, in consequence of 100

the flattening of the metal, give the seams a waved form and a length greater than the body of the plates.

3. A sheet-metal roof consisting of a series 5 of plates united or seamed together at their edges, the seams or joints being made of greater length than the surface or body portion of the roof, substantially as described and shown.

4. The herein-described method of preparing

sheet-metal roof-plates, consisting in corrugating a plate first in one direction and then in another, and finally elongating the edges of the plate.

JOHN O. VOGEL.
